SUCKER ROD BOX CLEANERS

Holt McWorkman, Tulsa, Okla.

Application June 28, 1954, Serial No. 439,695

8 Claims. (Cl. 134—47)

This invention relates to cleaning apparatus and more particularly to devices for cleaning the interior of hollow articles such as the boxes of sucker rod joints used in oil wells.

The sucker rods of oil wells are commonly united by so-called "pin and box" couplings comprising a box or socket member which is internally screw threaded and a pin member which screws into this box or socket.

The strain on these couplings is tremendous owing to the great length of the sucker rods, and it is, therefore, essential that the threaded joints be absolutely tight. In practice, sand and other foreign matter frequently becomes lodged in the threads of the sockets or boxes and it is of the utmost importance that this sand or the like be removed and the threads thoroughly cleaned before the coupling is made.

The object of the present invention is, therefore, to devise a simple and efficient device for cleaning the sockets or boxes of such couplings.

A further object is to devise such a device in which the working parts are so designed as to prevent sand and the like from entering the same and especially from working its way into the space between moving parts.

With the above and other objects in view and to improve generally on the details of such apparatus, the invention consists in the construction and combination of parts hereinafter described and claimed and illustrated in the accompanying drawings forming part of this specification, and in which:

Fig. 1 is a vertical central section through my improved cleaning device, showing a socket or box in position therein,

Fig. 2 is a plan view thereof on a smaller scale, the socket or box being omitted.

Fig. 3 is a fragmentary perspective view of the upper end of the cylindrical central part of the device, showing the spiral grooves therein,

Fig. 4 is a transverse section essentially on the line 4—4 of Fig. 1 looking in the direction of the arrows, and

Fig. 5 is a fragmentary side view of a sucker rod showing two couplings therein, parts being broken away and parts being shown in section.

Referring to the drawings in detail, my improved device consists of a body or container 1, preferably formed of cast metal, having around its upper edge a radially disposed flange 1^a.

Rising centrally from the center of the container and preferably cast integral therewith is a cylindrical member 2 which I shall call a piston. Above this piston is a cylinder 3 having a depending skirt portion 4 which surrounds the piston and engages the same with a sliding fit. The upper end of the cylinder 3 is closed by means of an end wall 5 having a conical upper surface 6.

A helical compression spring 7 fits within the hollow piston 2 and extends up into the cylinder 3, engaging the flat inner surface of the end wall 5 and tending to push the cylinder upwardly.

2

At a point normally just above the upper edge of the hollow piston 2, the cylinder 3 is formed with a plurality of openings or ports 8 which, as clearly shown in Figs. 1, are preferably disposed at an angle of about 45°.

- 5 The cylinder 3 is provided near its upper end with an annular shoulder 10 which projects beyond and overhangs the body of the cylinder, and is also provided near its lower end with a second annular shoulder 11 which overhangs the skirt 4.
- 10 The container 1 is provided with a cover or lid 12 which fits down upon the flange 1^a and is secured thereto by a plurality of bolts 13 preferably carrying wing nuts as clearly shown in Fig. 1. This cover or lid is formed with a central opening around which is a rim having a bevelled lower face shaped to conform with the slope of the conical upper surface 6 of the cylinder end 5. This surface is provided with a plurality of ribs or lugs 9, which form between themselves drainage channels permitting the return of the cleaning fluid to the container, as hereinafter described, these ribs or lugs engaging the bevelled surface 15 of the top or lid.

Projecting upwardly from the lid or cover 12 is a circular and slightly funnel shaped guide 14 which surrounds the opening in the cover.

- 20 The end wall 5 has a central screw threaded opening and into this opening is screwed the lower end 16^a of a nozzle 16 which projects up a substantial distance above the end wall 5 within the guide 14.

This nozzle is provided with a plurality of radially extending ports or passages, and between these ports or passages are set tufts of bristles or the like 17, forming a brush.

- 25 Referring more particularly now to Figs. 3 and 4, it will be seen that on the outside of the upper portion of the hollow piston 2 are formed a pair of spiral grooves 2^a and 2^b, preferably disposed at diametrically opposite points, and in these spiral grooves freely work a pair of pins 4^a and 4^b projecting inwardly from the skirt 4 of the piston 3, so that upon relative longitudinal movement of the piston 40 and cylinder, the cylinder is caused to rotate.

Referring to Fig. 5, sucker rods such as are used in oil wells are made up of sections A united at their ends by couplings each comprising a box or socket B and a pin C, screw threaded together.

- 45 In Fig. 1 I have illustrated one of these boxes B as in position for cleaning, this box being placed within the guide 14 and over and around the nozzle 16.

When the rod section carrying this box is pushed downwardly the spring 7 yields, permitting the cylinder 3 to descend. The spiral grooves above described result in the cylinder, together with the nozzle 16 and brush 17, being rotated within the box.

- The cleaning liquid employed is usually a light petroleum oil and it fills the container 1 nearly to the top, as indicated by the line x in Fig. 1. The liquid therefore enters through the ports 8 and fills the interior of both the piston and cylinder.

When, therefore, the cylinder is forced downwardly as above described, this liquid is trapped within the cylinder and piston by reason of the ports 8 being closed by the piston 2, after the manner of a sleeve valve, and the pressure therefore forces the liquid up into and through the nozzle 16, discharging it forcefully in the form of jets against the interior of the box B. At the same time the spiral grooves cause the nozzle and brush 17 to rotate, thus effectively brushing and removing from the threads of the box any sand or other foreign matter that may have accumulated thereon. The liquid and foreign matter being discharged from the lower end of the box flows down the conical surface 6 of the end wall of the cylinder between the lugs 9 and escapes around the edge of the

cylinder. It will be particularly noted that the annular shoulder 10 serves as a deflector to direct the returning liquid and foreign matter away from the outside of the cylinder. This deflecting action is increased by reason of the fact that the walls of the cylinder above the shoulder 10 are slightly inclined inwardly as clearly shown in Fig. 1.

Not only is the foreign matter deflected away from the cylinder by the shoulder 10, but it is prevented from entering the ports 8 by reason of the overhanging shoulder 11. Furthermore, the skirt 4 of the cylinder extends down far enough to completely cover the spiral grooves 2^a and 2^b at all times, thus preventing any sand or other foreign matter lodging in these grooves.

It will thus be seen that I have provided means for preventing the foreign matter from clogging entrance ports 8 and from becoming embedded between the piston and cylinder or in the spiral grooves, and it is thought that the many advantages of such an arrangement will be readily appreciated by those familiar with such matters.

It will be further noted that not only does the rim or flange 1^a serve to support the lid or cover but it also serves as a convenient handle by means of which the container may be picked up or transported. It will be seen that the lid or cover carrying the guide 14 may be readily removed when it is desired to inspect or clean out the interior of the container.

What I claim is:

1. A sucker rod box cleaner comprising a container, a hollow piston rigidly secured to and extending upwardly from the bottom of said container and having an open upper end, a cylinder surrounding and freely slideable over said piston, a removable cover for said container, and a spring within said piston and cylinder serving to hold the latter resiliently in engagement with said cover, the interior of said cylinder communicating with said container.

2. A sucker rod box cleaner comprising a container, a hollow piston rigidly secured to and extending upwardly from the bottom of said container and having an open upper end, a cylinder surrounding and freely slideable over said piston, a removable cover for said container having an opening co-axial with but of smaller diameter than said cylinder, the upper end of said cylinder being closed except for a relatively small central opening, an upwardly projecting nozzle set into said central opening, and a spring urging said cylinder upwardly against said cover, the interior of said cylinder communicating with said container.

3. A sucker rod box cleaner comprising a container, a hollow piston rigidly secured to and extending upwardly from the bottom of said container and having an open upper end, a cylinder surrounding and freely slideable over said piston, a cover for said container having an opening co-axial with but of smaller diameter than said cylinder, the upper end of said cylinder being closed except for a relatively small central opening, an upwardly projecting nozzle set into said central opening, an annular coupling guide carried by and projecting upwardly from said cover around the opening therein, said guide being spaced radially from said nozzle, and spring means urging said cylinder upwardly into contact with said cover, the interior of said cylinder communicating with said container.

4. A sucker rod box cleaner comprising a container, a hollow piston rigidly secured to and extending upwardly from the bottom of said container and having an open upper end, a cylinder surrounding and freely slideable over said piston, a cover for said container having an opening co-axial with but of smaller diameter than said cylinder, the upper end of said cylinder being closed by a wall having a conical upper surface, said wall having a relatively small opening at the center of the cone, a separately formed, removable, upwardly projecting nozzle set into said small opening, spring means urging the conical surface of the end wall of said cylinder into contact with the periphery of the opening in said cover, and means whereby liquid and foreign matter flowing from said conical surface are dis-

of the opening in said cover, and said conical surface having channels therein permitting the passage of liquid outwardly therealong past the area of contact with said cover into said container, the interior of said cylinder communicating with said container.

5. A sucker rod box cleaner comprising a container, a hollow piston rigidly secured to and extending upwardly from the bottom of said container and having an open upper end, a cylinder surrounding and freely slideable over said piston, a cover for said container having an opening co-axial with but of smaller diameter than said cylinder, the upper end of said cylinder being closed by a wall having a conical upper surface, said wall having a relatively small opening at the center of the cone, an upwardly projecting nozzle set into said small opening, spring means urging the conical surface of the end wall of said cylinder into contact with the periphery of the opening in said cover, and said conical surface having channels therein permitting the passage of liquid outwardly therealong past the area of contact with said cover into said container, the outside diameter of the said cylinder at a point immediately below said upper end wall being enlarged and the enlarged portion terminating in an annular shoulder overhanging the lower portion of the cylinder, whereby liquid flowing from said conical surface is discharged as a cascade from said overhanging shoulder clear of the side walls of the lower portion of said cylinder.

6. A sucker rod box cleaner comprising a container, a hollow piston rigidly secured to and extending upwardly from the bottom of said container and having an open upper end, a cylinder surrounding and freely slideable over said piston, a cover for said container having an opening co-axial with but of smaller diameter than said cylinder, the upper end of said cylinder being closed by a wall having a conical upper surface, said wall having a relatively small opening at the center of the cone, an upwardly projecting nozzle set into said small opening, spring means urging the conical surface of the end wall of said cylinder into contact with the periphery of the opening in said cover, and said conical surface having channels therein permitting the passage of liquid outwardly therealong past the area of contact with said cover into said container, said cylinder having intake ports formed through the wall thereof at a point lying just above the top edge of said piston when the cylinder is in its uppermost position, the outside diameter of the said cylinder at a point immediately below said upper end wall being enlarged, and the enlarged portion terminating in an annular shoulder overhanging that portion of the cylinder wall in which said intake ports are formed, whereby liquid and foreign matter flowing from said conical surface are discharged as a cascade from said overhanging shoulder, clear of said ports.

7. A sucker rod box cleaner comprising a container, a hollow piston rigidly secured to and extending upwardly from the bottom of said container and having an open upper end, a cylinder surrounding and freely slideable over said piston, a cover for said container having an opening co-axial with but of smaller diameter than said cylinder, the upper end of said cylinder being closed by a wall having a conical upper surface, said wall having a relatively small opening at the center of the cone, an upwardly projecting nozzle set into said small opening, spring means urging the conical surface of the end wall of said cylinder into contact with the periphery of the opening in said cover, and said conical surface having channels therein permitting the passage of liquid outwardly therealong past the area of contact with said cover into said container, said cylinder having intake ports formed through the wall thereof at a point lying just above the top edge of said piston when the cylinder is in its uppermost position, and means whereby liquid and foreign matter flowing from said conical surface are dis-

charged as a cascade, clear of that portion of the side walls of the cylinder in which said ports are formed.

8. A sucker rod box cleaner comprising a container, a hollow piston rigidly secured to and extending upwardly from the bottom of said container and having an open upper end, a cylinder surrounding and freely slideable over said piston a spring within said piston and cylinder tending to move the latter upwardly, and means to limit the upward movement of said cylinder, the wall of said cylinder having an annular overhanging shoulder, and having intake ports extending therethrough at a point immediately below said shoulder and lying just above

5

the upper edge of said piston when said cylinder is in its uppermost position.
